CLAIM

The ornamental design for a femoral implant component as shown and described.

DESCRIPTION

FIG. 1 is a front perspective view from above of the claimed design;

FIG. 2 is a left side perspective view from above of the claimed design of FIG. 1;

FIG. 3 is a right side perspective view from above of the claimed design of FIG. 1;

FIG. 4 is a front perspective view from below left of the claimed design of FIG. 1;

FIG. 5 is front perspective view from below right of the claimed design of FIG. 1;

FIG. 6 is a top view of the claimed design of FIG. 1;

FIG. 7 is a bottom view of the claimed design of FIG. 1;

FIG. 8 is a front view of the claimed design of FIG. 1;

FIG. 9 is a rear view of the claimed design of FIG. 1;

FIG. 10 is a right side view of the claimed design of FIG. 1; and,

FIG. 11 is a left side view of the claimed design of FIG. 1.

(Continued)

The ornamental design which is claimed is shown in solid lines in the drawings. The broken lines in the drawings are for illustrative purposes only and form no part of the claimed design.

1 Claim, 8 Drawing Sheets

Related U.S. Application Data

division of application No. 29/544,891, filed on Nov. 6, 2015, now Pat. No. Des. 849,945, which is a division of application No. 29/466,148, filed on Sep. 4, 2013, now Pat. No. Des. 744,104, which is a continuation-in-part of application No. 13/340,645, filed on Dec. 29, 2011, now Pat. No. 8,911,501, and a continuation-in-part of application No. 13/340,636, filed on Dec. 29, 2011, now Pat. No. 9,649,195.
